[57] CLAIM

The ornamental design for golf putter, as shown and described.

DESCRIPTION

FIG. 1 is a front elevational view of a gold putter according to the present design;

FIG. 2 is a rear elevational view of the golf putter of FIG. 1;

FIG. 3 is a side elevational view of one side of the golf putter of FIG. 1;

FIG. 4 is a side elevational view of the opposite side of the golf putter as shown in FIG. 3;

FIG. 5 is a top plan view of the golf putter of FIG. 1; FIG. 6 is a bottom plan view of the golf putter of FIG. 1; and,

FIG. 7 is a perspective view of the golf putter of FIG. 1 looking from the front, top and right side.

The broken line showing of a ball in FIG. 7 is for illustrative purposes only.
